CLAIM

The ornamental design for a game apparatus, as shown and described.

DESCRIPTION

FIG. 1 is a perspective view of the game apparatus of the instant invention;

FIG. 2 is a perspective view of the board assembly portion thereof, shown separately for ease of illustration;

FIG. 3 is a top plan view of the board assembly portion thereof;

FIG. 4 is a bottom plan view of the board assembly portion thereof;

FIG. 5 is a front elevational view of the board assembly portion thereof;

FIG. 6 is a right side elevational view of the board assembly portion thereof;

FIG. 7 is a rear elevational view of the board assembly portion thereof;

FIG. 8 is a left side elevational view of the board assembly portion thereof;

FIG. 9 is a perspective view of the cat figure portion thereof, shown separately for ease of illustration;

FIG. 10 is a right side elevational view of the cat figure portion thereof;

FIG. 11 is a left side elevational view of the cat figure portion thereof;

FIG. 12 is a front elevational view of the cat figure portion thereof;

FIG. 13 is a rear elevational view of the cat figure portion thereof;

FIG. 14 is a top plan view of the cat figure portion thereof;

FIG. 15 is a bottom plan view of the cat figure portion thereof;

FIG. 16 is a perspective view of the mouse figure portion thereof, shown separately for ease of illustration;

FIG. 17 is a right side elevational view of a mouse figure portion thereof;

FIG. 18 is a left side elevational view of a mouse figure portion thereof;

FIG. 19 is a front elevational view of a mouse figure portion thereof;

FIG. 20 is a rear elevational view of a mouse figure portion thereof;

FIG. 21 is a top plan view of a mouse figure portion thereof; and,

FIG. 22 is a bottom plan view of a mouse figure portion thereof.
